US0D1014857S

(12) **United States Design Patent** (10) **Patent No.:** **US D1,014,857 S**
(45) **Date of Patent:** **** Feb. 13, 2024**

(54) **FOOT CALLUS MANAGEMENT BAR**

(71) Applicant: **Sandbar Hand Care, LLC**, Payson, UT (US)

(72) Inventor: **RyLee Reid**, Payson, UT (US)

(73) Assignee: **Sandbar Hand Care, LLC**, Payson, UT (US)

(**) Term: **15 Years**

(21) Appl. No.: **29/751,005**

(22) Filed: **Sep. 17, 2020**

(51) LOC (14) Cl. **28-03**

(52) U.S. Cl.

USPC **D28/59**

(58) **Field of Classification Search**

(57) **CLAIM**

The ornamental design for a foot callus management bar, as shown and described.

DESCRIPTION

FIG. 1 is a top front perspective view of a foot callus management bar in accordance with my invention;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a back view thereof.

The broken lines in the drawings illustrate portions of the foot callus management bar that form no part of the claim.
